United States Patent Office

Des. 212,183
Patented Sept. 10, 1968

212,183

BOTTLE

Arthur F. Hileman, San Francisco, Calif., assignor to Safeway Stores Incorporated, Oakland, Calif., a corporation of Maryland

Filed Jan. 10, 1967, Ser. No. 5,368

Term of patent 14 years

(Cl. D9—115)

FIG. 1.

FIG. 2.

FIGURE 1 is a front elevational view of a bottle showing my new design, the rear being the same in appearance; FIGURE 2 is a side elevational view; and

FIGURE 3 is a top plan view thereof.

I claim:

The ornamental design for a bottle, as shown and described.
